UNITED STATES PATENT OFFICE.

OSWALD S. PULLIAM, OF PITTSBURGH, PENNSYLVANIA.

UNDERFRAME CENTER-SILL CONSTRUCTION FOR CARS AND THE LIKE.

1,159,534.

Specification of Letters Patent.

Patented Nov. 9, 1915.

Application filed September 23, 1909. Serial No. 519,131.

To all whom it may concern:

Be it known that I, OSWALD S. PULLIAM, a resident of Pittsburgh, in the county of Allegheny and State of Pennsylvania, have 5 invented certain new and useful Improvements in Underframe Center-Sill Construction for Cars and the like, of which the following is a specification.

This invention relates to an improved 10 underframe construction for cars, and the like, and the present invention more particularly relates to a new and improved center-sill or a center-sill constructed in accordance with the principle of the cantilever.

15 An object of my invention is to depart from the usual and well known truss construction and to substitute therefor, in a steel underframe for cars, and the like, a center-sill of cantilever construction.

20 In the accompanying drawings, which illustrate applications of my invention, Figure 1 is a perspective view of a car-body underframe embodying my invention; Fig. 2, a perspective view particularly showing an 25 end portion of the center-sill of a slightly modified form from that shown by Fig. 1.

Referring to the drawings and first to the 30 form of Fig. 1, the center-sill comprises two end-portions 2 and 3 each preferably formed as an integral casting and respectively designed to be mounted on and supported by the respective truck bolsters 4. As illustrated, both end-portions are formed with a center plate member 5 designed, when the 35 end-portions are mounted on the truck-bolsters, to bear on the center plate members of said bolsters. Each of the end-portions 2 and 3 comprises laterally extending members 6 and in the form of Fig. 1 members 6 40 constitute a body-bolster. The casting constituting the end-portions of the center-sill projects forwardly and rearwardly of the respective truck bolsters 4 for about an equal distance and the outer members are provided with means or members 7 adapted to engage the draft-rigging, not shown. In Fig. 1, I have shown the forward end-portion 45 of the center-sill extended to and located in the respective end-sills 8 of the body

underframe. By this arrangement, and 50 particularly with the free end of the outer member extending into the opening 8' in the end sill, shearing strains at the point of connection of such outer members and the end sill will be taken up, in addition to 55 which, the draw-bar connection is retained out of contact with the sides of the opening and the lateral strains thereof placed on the outer members, the latter, being in turn supported by such side walls of the opening. 60

The end portions 2 and 3, of the center-sill, are connected by suitable connecting means 9. In the drawing I have shown two members of channel form as the connecting means, with said members riveted to the 65 end-portions 2 and 3. The laterally extending or cross sills 10 are secured to the central or connecting member of the center-sill and extend outwardly therefrom to the respective side-sills 11. 70

In the form of Fig. 2 I have shown a slightly different construction of the end portions of the center-sill from that shown by Fig. 1. In this latter form I have shown the laterally extending members 6 arranged 75 between the middle of the end portions of the sill and the forward and rear ends thereof.

What I claim is:

1. In an underframe construction for cars 80 and in combination, a pair of body bolster castings each having integral members on opposite sides of the bolster and extending in correspondence with the longitudinal center of the underframe, said members being 85 of substantially equal length, individual side and end sills, said side sills connecting corresponding bolster ends and having an integral length substantially equal to the distance between the free ends of the outer 90 members of the casting, said end sills having openings to receive the ends of said outer members and being secured to the ends of the side sills, and means for connecting the free ends of the inner members 95 of the castings, said means and the inner and outer members of the casting constituting the center sill structure.

2. In an underframe construction for cars and in combination, a pair of body bolster castings each having a bolster member and integral oppositely-extending members to provide a substantially balanced construction with the inner members connected with means to form a center sill structure, side sills, and end sills secured to the side

sills, the free ends of the outer members extending into openings in the end sills. 10

In testimony whereof I affix my signature in presence of two witnesses.

OSWALD S. PULLIAM.

Witnesses:

A. C. WAY,
W. G. DOOLITTLE.
